(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of the claimed design; and, FIG. 2 is a second image thereof.

The outermost broken lines in the figures show a display screen or portion thereof, and form no part of the claimed design. The other broken lines in the figures show portions of the animated graphical user interface that form no part of the claimed design.

The appearance of the animated image sequentially transitions between the images shown in FIGS. 1 and 2. The process or period in which one image transitions to another forms no part of the claimed design.

1 Claim, 2 Drawing Sheets

FIG. 1

DUCT AIR FILTERS

These filters are typically used as replacement filters in HVAC equipment. They have a flexible steel grill bonded to one side for support.

All meet MERV 5 performance requirements. Actual size is up to 50% less than trade size.

Duct size	Filter	Removes Particulate Size	Frame	Max. Temp. °F	Pkg. Qty.	Pkg. F.R.
10x10	Filter	Down To, microns	Material			

Duct size chart

The MERV system is an industry standard that rates air filters on a scale from 1 to 10 based on how well they remove particles in three size ranges. A higher rating means a filter removes more particles.

Prefilter

Protects HVAC equipment and extends the life of other, higher-efficiency filters. Prefilters capture large particles, such as standing dust, textile fibers, and mold spores.

MERV 5

Unfiltered Air Filter   Filtered Air

MERV 5 filters remove at least 20% of large particles (2 to 10 microns), such as mold spores and cement dust.

MERV 6

Unfiltered Air Filter   Filtered Air

MERV 6 filters remove at least 35% of large particles (2 to 10 microns), such as mold spores and cement.
